UNITED STATES PATENT OFFICE.

GUY B. WAITE, OF NEW YORK, N. Y.

REINFORCED-CONCRETE BUILDING CONSTRUCTION.

1,141,160.

Specification of Letters Patent. Patented June 1, 1915.

Application filed August 17, 1911. Serial No. 644,685.

To all whom it may concern:

Be it known that I, GUY B. WAITE, a citizen of the United States, and resident of the borough of Queens, county of Queens, 5 city and State of New York, have invented certain new and useful Improvements in Reinforced-Concrete Building Construction, of which the following is a specification.

This invention relates to a steel and concrete construction for buildings in which a self-supporting steel skeleton frame is erected ahead of the concrete, said skeleton frame giving lines for the erection of the forms which are hung to and temporarily 10 supported by said frame, said forms being adapted to receive and to serve as molds for the concrete. Subsequent to the erection of the concrete the steel and the concrete form together a truly reinforced structure 15 wherein the concrete takes up the compressional strains and the steel the tensional strains. To this end the steel entering into 20 the floor construction is arranged so that in the completed structure it will be in tension 25 only.

It is well-known that in most self-supporting steel skeleton constructions the steel is made to carry the entire load of the floors, the concrete floors being formed between and around the steel. In this form of 30 construction the steel is distributed throughout the concrete in a manner which does not permit of separating the stresses of the steel from those of the concrete.

In reinforced concrete constructions of 35 the ordinary type the stresses in the steel and in the concrete are segregated by means of steel rods placed in the tensional zone of the floors to take up tension, the steel 40 being omitted from the compressional part of the floors so that the compressional stresses will be taken up by the concrete.

The advantage of the steel skeleton first mentioned is the facility of erection. In 45 this form of construction several floors can be worked on simultaneously by the workmen. However, this form of construction requires careful and accurate fabrication of all of the steel parts, and by reason of this, 50 great delay is occasioned in starting a building.

The great economy of the reinforced concrete construction is in the amount of steel saved. Another advantage of the rein-

forced construction is the facility with 55 which a building is started. The steel rods used for the reinforcement need practically no fabrication and the building may be started with rods which are ordinarily carried in stock. However, its erection for several stories is slower than the steel skeleton construction because it must be erected one story at a time with wooden forms, the steel bars being put in place after the forms are set. 60

Some attempts have been made to produce a light steel construction which could be erected like an all-steel skeleton construction, said skeleton to be subsequently incased and embedded in concrete, but in all 70 of these attempts the steel parts must be fabricated, that is to say, cut and punched in accordance with detailed plans. The planning and the fabrication of this light steel requires substantially the same skill 75 and care and delay that a primary steel frame construction requires.

It is one of the main objects of this invention to construct a steel skeleton frame from ordinary standard shapes and sizes of 80 material, without special fabrication and to embed said frame in concrete to form a truly reinforced concrete construction. To accomplish this I use light steel angles and beams of the regular commercial shapes and 85 lengths and secure said material together by suitable clamps, the steel being so disposed as to take up the tensional strains in the floors, the concrete taking up the compression strain. 90

Another object of the invention is to provide means in a built-up self-supporting steel skeleton frame or structure, to take up the negative bending movement over points of support. By this arrangement the 95 amount of steel necessary is reduced. It is, therefore, manifest that this invention eliminates the special fabrication of the steel forming the independent self-supporting structure, thereby securing the advantage 100 of the reinforced concrete construction in which unfabricated bars are used in the tensional zone of the concrete.

Another advantage of the invention is that a building may be started from an 105 ordinary stock of material and without the necessity of specially fabricating the said material, thereby securing the other advan-

tage of the ordinary bar reinforced concrete construction.

Another object of the invention is to provide a construction wherein the work of erecting the steel frame may proceed ahead of the concrete work, thereby securing the advantage of the primary steel frame construction. It will, therefore, be seen that by my invention I secure the advantages of the concrete construction which is merely reinforced by rods and also secure the advantages of the primary steel frame construction.

In the drawings Figure 1 is a side elevation of a pair of columns or supports with a girder construction extending between said supports, the concrete being omitted; Fig. 2 a plan view thereof; Fig. 3 a horizontal sectional view through one of the columns; Fig. 4 a transverse vertical sectional view through the floor girder; Fig. 5 a detail view of one of the anchoring clamps on the columns; Fig. 6 a detail cross sectional view on the line VI—VI of Fig. 2 showing the means for spacing apart the two members of the floor girder; Fig. 7 a horizontal sectional view through two columns similar to Fig. 2, showing a slightly modified form of girder extending between said columns; Fig. 8 a detail view showing my improved floor girder construction applied to an ordinary steel column; Fig. 9 a side elevation of the construction shown in Fig. 8; Fig. 10 a plan view showing another method of applying my invention to an ordinary steel column; Fig. 11 a detail horizontal sectional view showing the means for clamping the floor beam members to the supporting bars of the columns; Fig. 12 a vertical sectional view of a portion of a column showing the fastening means illustrated in Fig. 11. Fig. 13 a detail horizontal sectional view showing a modified arrangement of columns and floor beams; and Fig. 14 a side elevation of the construction shown in Fig. 13.

Referring to the various parts by numerals, 1 designates the vertically arranged angle bars which form the columns for the building. As shown in Fig. 2, four of these angle irons are preferably employed, each iron forming one corner of the rectangular column structure. These angle irons are used in the ordinary standard lengths and are connected together at their ends by means of any suitable form of clamps. I preferably secure them in place by a clamp 2 consisting of two angle irons which embrace the abutting ends of the irons and are secured together by bolts or other suitable securing devices. In this manner the columns may be carried to any desired height. Somewhat below the floor level and approximately on the ceiling level, anchoring clamps 3 are secured to the angle-irons 1

of the columns. These clamps form temporary supports for the floor structure. On the columns just above the anchoring clamps are secured floor-supporting clamps 4. These floor supporting clamps are connected together by transverse brace rods 5, said rods resting against the inner sides of the column irons 1. The bolts 6 which connect the said irons with the ends of said clamps do not extend through the column irons but serve merely as a means to cause the clamps to grasp the column irons so that said clamps and the bars 5 only frictionally engage the column irons. The floor supporting clamps are designed to rest on the anchoring clamps. The column irons are connected together by a series of transverse cross bars 5^a and clamps 4^a to give the column the necessary strength and rigidity to temporarily take up the working loads on the structure, said clamps and bars being the same in construction as clamps 5 and bars 4.

The cross bars 5 form supports for the floor beams 7 which extend from one column to the adjoining column. The ends of the floor beams extend within the column any suitable distance and for that reason need not be accurately cut to lengths. It is manifest that they may extend into the column more or less according to their length. These floor beams are preferably made up of two channel iron members separated a suitable distance from each other for the greater portion of their length, said separate members being curved inwardly or converged toward their ends so that their ends within the column frame are close together. To maintain said beam members separated I provide a separator device 8 adapted to fit between the said beam members, said spacing device consisting of a plate 9 adapted to fit between the members and the clips 10 adapted to embrace the upper and lower flanges thereof, as shown clearly in Fig. 6. It will, of course, be understood that any form of device for maintaining these beam members separated until the concrete is poured, may be employed.

Above the ends of the floor beams, and extending through each column, is a short reinforcing beam 11, said beam extending outwardly beyond the column a suitable distance and directly over the main floor beams, as clearly shown in Fig. 2. This reinforcing beam is formed of two channel iron members arranged side by side and spaced apart a suitable distance for the greater portion of their length, their ends being brought close together, as shown clearly in Figs. 2 and 3 of the drawings. Extending along the top of these beams 11 and then downwardly to the beams 7 is a bar 12, said bar being close to the floor beams 7 for a considerable portion of its 13.

length, the said bar distributing the strain which is brought on the floor beam to and throughout the reinforcing beam 11. The beams 11 take up the negative bending movement over the points of support for the floor beams, the tensional strains at the ends of the reinforced concrete floor beams being taken up by them. By this arrangement a considerable saving in steel is effected for the reason that the floor beams may be made much lighter than would be necessary if these beams 11 were not employed. The ends of the short reinforcing beams 11 are connected to the floor beams 7 by means of vertical bolts 13, said bolts serving to stiffen the floor beams until the concrete is in place.

The object of separating the members of the floor beams and the members of the reinforcing beams, is to permit the concrete to flow in between said beam members so that they will be firmly embedded and united with the concrete; and the object of converging the ends of said beams is to 25 so arrange them that they will resist shearing stresses brought thereon tending to cause them to shear the concrete. By arranging the ends of the beams on the converging lines the tendency of the beams to shear the concrete is reduced to a minimum. It is manifest that the same result may be obtained by placing the beam members close together midway between their ends and then spreading the ends of the beams. In 30 this way the lines of the beams will extend diagonally across the lines of shearing stresses and will successfully resist them. The reinforcing beams 11 may be supported in any suitable manner and extend 35 through the columns, as shown clearly in Figs. 1 and 2. In Fig. 1 these reinforcing beams are shown as supported by spacing pieces 14 which rest upon the beams 7.

To take up the shearing stresses shear 40 bars 15 are bent around the floor beams 7 and are carried to a point slightly above the reinforcing beams 11, as shown clearly in Figs. 1 and 4 of the drawings. These shear bars adjacent to the columns embrace 45 the reinforcing beams. As shown clearly in Fig. 4 the floor beams are arranged wholly in the tensional zone of the reinforced concrete floor beam except those portions thereof which extend under the reinforcing beams, the tensional stresses being transmitted to said reinforcing beams at the ends of the floor beams. The shear bars extend from the tensional zone up into the compressional zone and terminate just below the floor level.

The floor beams may be clamped to the cross bars 5 by any suitable means. I preferably use a clamping yoke 16 which extends diagonally across the floor beams and 55 the cross bar, as shown clearly in Fig. 11,

the cross bar of the yoke extending under the bar 5. Nuts are threaded on the ends of the yoke so that the floor beams may be very rigidly clamped to the bars 5. A similar clamping means may be used to connect 70 the reinforcing beams 11 with their supports 14, but this is not necessary for the reason that said beams will be held in position with sufficient rigidity by the bolts 13 and the bars 12. The bolts 13 pass through plates 17 75 placed above the beams 11 and below the floor beams 7 so that said bolts serve as a clamping means to hold the beams 11 in position with respect to the floor beams 7.

It is manifest that with my invention a 80 steel skeleton may be formed of unfabricated steel of standard shapes and sizes which will be amply strong to support the forms and molds and to form a working platform of sufficient strength to carry the 85 working loads, and which will form the reinforcing members of a truly reinforced concrete construction. It is manifest that the column irons may be of any shape in cross section, and of any length. Their 90 length need have no relation to the height of the ceilings in the building, for the reason that the anchoring clamps may be secured to the column irons at any desired point thereon. It is also manifest that the 95 floor beams need not be accurately fabricated and may extend more or less into the skeleton column construction, the floor beam clamping devices being such that the 100 floor beams may be secured at any point.

In Fig. 7 is illustrated a slightly different form of floor beam. In this construction a single metal floor beam member 7^a extends between the columns and carries a supplemental metal floor beam member 7^b, this latter member terminating short of the columns and being carried entirely by the main floor beam member. Suitable spacing devices 8^a are employed to hold the two floor beam members separated, and the ends of the supplemental member are bent inwardly toward the main member to enable said members to 105 resist the shearing stresses brought thereon and tending to disrupt or break the union between the concrete and the steel beam. 110

In Fig. 8 I have shown my invention partially applied to a steel column of ordinary fabricated construction. In this arrangement of the invention the converged ends of the metal floor members 7^b are supported on 120 a bracket 18 secured to the side of the column. To the sides of the column substantially parallel with the floor beams are arranged short reinforcing metal beams 11^a, the ends of these beams being connected by 125 bolts 19 and plates 20 to the floor beams 7^a. By means of this construction the negative bending movement is transmitted to and taken up by the reinforcing beams 11^a. In Fig. 10 this portion of the invention is 130

shown as applied to an ordinary I-beam column. In this construction the reinforcing beams 11^b are secured to the outer sides of the column while the floor beam 7^a rests 5 upon brackets 21 secured to the web of the I-beam. Any other form of cast or steel column may be used with the main and reinforcing beams.

In Figs. 13 and 14 the floor beams 7^a are 10 arranged outside of the column irons, the ends of said beams resting on brackets 22 secured to the sides of said column. It is manifest that in this arrangement the floor beams may extend beyond the columns, as 15 shown clearly in these figures, and consequently they need not be cut to specified lengths. In this arrangement of the floor beams the reinforcing beams 11^b may be passed through the column irons, as shown 20 clearly in these figures. The ends of these reinforcing beams may be connected to the floor beams by the vertical bars 23. It is, therefore manifest that the floor beams used as shown in Figs. 1 and 2 or as shown in 25 Figs. 13 and 14 need not be cut to specified lengths, as in the one case they may extend into the column more or less, according to length, and in the other case they may extend more or less beyond the column.

30 As shown in Figs. 13 and 14 the floor beams may be bent to extend inwardly toward each other between the columns, for a purpose hereinbefore fully set forth.

In arranging the column irons one above 35 the other, as shown in Fig. 1 their ends are preferably brought together and secured by means of a set of clamps 4^a as shown in Fig. 1.

Having thus fully described my invention, 40 what I claim as new and desire to secure by Letters Patent, is:

1. A reinforced concrete construction comprising a skeleton column frame made up of light, unfabricated angle irons, clamps for 45 securing said angle irons together at their ends, anchoring clamps secured about said irons at the ceiling height, floor beam supporting clamps secured to said irons above the anchoring clamps, column braces connecting together said floor beam supporting clamps, a floor beam projecting into said columns, shear bars carried by said floor beams, and concrete embedding the column frame, floor beams and shear bars.

50 2. A reinforced concrete structure comprising a series of columns of light skeleton steel construction formed of a plurality of angle irons vertically arranged and abutting together at their ends, frictional clamping means extending around the ends of said irons, friction floor-anchoring clamps secured to said column irons at any suitable points, supporting bars connected to said clamps, floor beams supported by said bars 55 and extending into the columns, reinforcing

beams extending through the columns above the floor beams and slightly below the upper surface of the finished floor, and a mass of concrete embedding the columns, floor beams and reinforcing beams.

3. A reinforced concrete structure comprising a series of skeleton columns, each of said columns being made up of light iron members vertically arranged and placed end to end, frictional clamps extending around 70 said column irons and clamping them together, anchoring clamps extending around the column irons, floor beam-supporting clamps extending around said irons and resting on the anchoring clamps, floor beam- 75 supporting bars carried by these latter clamps, floor beams resting on said floor beam-supporting bars, and a mass of concrete embedding the columns and the floor beams.

4. A reinforced concrete structure comprising a series of skeleton columns, each of said columns being made up of light angle irons vertically arranged and abutting together at their ends, frictional clamps extending around 80 said column irons and clamping them together, floor beam-anchoring clamps extending around the column irons, floor beam-supporting clamps extending around said irons and resting on the anchoring clamps, floor beam-supporting bars carried by these latter clamps, floor beams resting on said floor beam supporting bars, reinforcing bars extending through 85 the columns above the floor beams and projecting a suitable distance on opposite sides of the columns, shear bars extending from the floor beams upwardly to a point above the reinforcing beams, some of said shear bars embracing the reinforcing beam, and 90 a mass of concrete embedding said column irons, floor beams, reinforcing beams and shear bars.

5. A reinforced concrete structure comprising a series of skeleton columns, each of said columns being made up of light iron members vertically arranged and placed end to end, frictional clamps extending around 95 said column irons and securing them together, anchoring clamps secured to said irons, floor beam supporting clamps secured on said irons and resting on the anchoring clamps, floor beam supporting bars carried by these latter clamps, floor beams resting 100 on said floor beam supporting bars and consisting of a pair of members arranged side by side in the same horizontal plane and separated from each other for a suitable distance, the ends of said floor beam members extending into the column structures and 105 converging toward said ends, and a mass of concrete embedding the columns and floor beams.

6. A reinforced concrete structure comprising a series of skeleton columns, each 110

of said columns being made up of light iron members vertically arranged and placed end to end, frictional clamps extending around said column irons and securing them together, anchoring clamps secured to said irons, floor beam supporting clamps secured on said irons and resting on the anchoring clamps, floor beam supporting bars carried by these latter clamps, floor beams resting on said floor beam supporting bars and consisting of a pair of members arranged side by side in the same horizontal plane and separated from each other for a suitable distance, the ends of said floor beam members extending into the column structures and converging toward said ends, a reinforcing beam extending through each column above the floor beam and projecting a suitable distance beyond the column, said reinforcing beams each consisting of two members arranged side by side in the same horizontal plane and separated a suitable distance from each other and converging toward their ends, and a mass of concrete embedding the columns, floor beams and reinforcing beams.

7. A reinforced concrete structure comprising a series of skeleton columns, each of said columns being made up of light iron members vertically arranged and placed end to end, frictional clamps extending around said column irons and securing them together, anchoring clamps secured to said irons, floor beam supporting clamps secured on said irons and resting on the anchoring clamps, floor beam supporting bars carried by these latter clamps, floor beams resting on said floor beam supporting bars and consisting of a pair of members arranged side by side in the same horizontal plane and separated from each other for a suitable distance, the ends of said floor beam members extending into the column structures and converging toward said ends, a reinforcing beam extending through each column above the floor beam and projecting a suitable distance beyond the column, said reinforcing beams each consisting of two members arranged side by side in the same horizontal plane and separated a suitable distance from each other and converging toward their ends, a reinforcing bar arranged close to the floor beam and extended up to the ends of the reinforcing beams, shear bars embracing the floor beams, reinforcing beams and reinforcing bars, and a mass of concrete embedding the columns, floor beams, reinforcing beams and shear bars.

8. A reinforced concrete structure comprising a series of skeleton columns each being made up of light angle iron members vertically arranged and clamped together at their ends, independent anchoring clamps extending around the column irons and adapted to be vertically adjusted thereon to any desired position, floor beam supporting clamps

extending around the irons and resting on the anchoring clamps, floor beams supported by the floor beam clamps and extending into the skeleton columns, whereby said floor beams may be of variable lengths and will be supported in position by the floor beam clamps and anchoring clamps, and a mass of concrete embedding the columns and floor beams.

9. A reinforced concrete structure embodying a series of columns and a series of floor structures, each floor structure comprising reinforced concrete girders each reinforced by two one-piece steel members positioned in the same horizontal plane wholly below the neutral axis of the completed girder, two reinforcing beams above the girder reinforcing members said reinforcing beams being in the same horizontal plane and extending outwardly from the columns a suitable distance in the upper portion of the reinforced girders, the ends of the reinforcing beams and the ends of the girder reinforcing members curving inwardly toward each other, rigid bars connecting the outer ends of the reinforcing beams to the girder members directly below, said girder members and reinforcing beams being interconnected with said columns to form a light steel skeleton structure whose strength is only sufficient to support the temporary loads during the erection of the building whereby said steel reinforcing skeleton can be erected previous to the application of the concrete and will form a working support during the application of the concrete, said independent steel structure becoming the reinforcing means of the completed concrete structure and disposed wholly within the tensional zone thereof.

10. A reinforced concrete construction comprising a series of columns of skeleton steel construction, floor beams extending into said columns said beams being formed of two members arranged in the same horizontal plane and separated from each other a suitable distance, the end portions of said members extending inwardly toward each other whereby said end portions will be substantially oblique to the longitudinal line of the floor beams, a part of said oblique end portions of the said beams being outside of the skeleton columns, and a mass of concrete embedding said floor beams and columns, the floor beams being below the neutral axis of the concrete beam and wholly in the tensional zone thereof.

11. A reinforced concrete structure comprising a series of columns of light skeleton steel construction formed of a plurality of bars vertically arranged and abutting together at their ends, clamping means at the ends of said bars, floor anchoring clamps secured to said column bars at suitable points, floor beams supported by said clamps and

extending into the columns, reinforcing beams extending through the columns above the floor beams and slightly below the upper surface of the finished floor, and rigid means connecting the ends of the reinforcing beams to the floor beams directly below, and a mass of concrete embedding the columns, floor beams and reinforcing beams.

12. A reinforced concrete structure comprising a series of columns formed of a plurality of bars vertically arranged and abutting together at their ends, clamping means at the ends of said bars, floor beams supported by said vertical bars and extending into the columns, the end portions of said beams being oblique to the longitudinal line of the beam but in the same horizontal plane, reinforcing beams extending through the columns above the floor beams and slightly below the upper surface of the finished floor, the end portions of said reinforcing beams extending beyond the columns and being oblique to the longitudinal line of the beam but in the same horizontal plane therewith, rigid means connecting the ends of the reinforcing beams to the floor beams at a point beyond the columns, and an integral mass of concrete embedding the columns, floor beams and reinforcing beams.

13. A reinforced concrete construction comprising a skeleton column frame formed of vertical bars, means for securing said bars together, floor beams clamped to said bars and projecting into said columns, the end portions of said beams being oblique to the longitudinal line of the beams but in the same horizontal plane therewith, said floor beams being wholly below the neutral axis of the completed concrete beams, reinforcing beams extending through the columns above the floor beams and extending out beyond the columns a suitable distance, the end portions of said reinforcing beams being oblique to the longitudinal line of the beams but in the same horizontal plane therewith, means rigidly connecting the outer ends of the reinforcing beams to the floor beams at a point beyond the columns, and an integral mass of concrete embedding

the columns, floor beams and reinforcing beams.

14. A reinforced concrete construction comprising a series of columns of skeleton steel construction, floor beams, said beams being formed of two members arranged in the same horizontal plane and separated from each other, the ends of said beams extending inwardly toward each other as they approach the column, a reinforcing beam formed of two members arranged in substantially the same horizontal plane and extending through the columns above the floor beams but below the upper surface of the finished floor said members of the reinforcing beam converging or extending inwardly toward each other at their ends and rigid means connecting the ends of the reinforcing beams to the floor beams, and an integral mass of concrete embedding the columns, floor beams and reinforcing beams.

15. A reinforced concrete construction comprising a series of columns of skeleton steel construction, floor beams, said beams being formed of two members arranged in the same horizontal plane and separated from each other, the ends of said beams extending inwardly toward each other as they approach the column, a reinforcing beam formed of two members arranged in substantially the same horizontal plane and extending through the columns above the floor beams but below the upper surface of the finished floor said members of the reinforcing beam converging or extending inwardly toward each other at their ends, rigid means connecting the ends of the reinforcing beams to the floor beams, an integral mass of concrete embedding the columns, floor beams and reinforcing beams, and shear resisting bars extending upwardly from the floor beams, some of said bars encircling the reinforcing beams.

In testimony whereof I hereunto affix my signature in the presence of two witnesses.
